[57] CLAIM

The ornamental design for a machining center, as
shown and described.

DESCRIPTION

FIG. 1 is a front elevational view of a machining center
showing our new design;

FIG. 2 is a rear view thereof;

FIG. 3 is a side elevational view taken from the right of
FIG. 1;

FIG. 4 is a side elevational view taken from the left of
FIG. 1;

FIG. 5 is a top plan view thereof;

FIG. 6 is a bottom plan view thereof; and

FIG. 7 is a perspective view thereof.
